US00D507570S

(12) **United States Design Patent** (10) Patent No.: **US D507,570 S**
Ozolins et al. (45) Date of Patent: **** Jul. 19, 2005**

(54) **MULTI-PANEL COMPUTER DISPLAY**

(75) Inventors: **Helmars E. Ozolins**, Orient, NY (US); **Masamichi Udagawa**, New York, NY (US); **Alfonso Castagna**, Etobicoke (CA); **Christopher J. H. Stewart**, Toronto (CA); **Alexander Chong**, Thornhill (CA); **Sigrid G. Moeslinger**, New York, NY (US)

(73) Assignee: **Bloomberg LP**, New York, NY (US)

(**) Term: **14 Years**

(21) Appl. No.: **29/209,177**

(22) Filed: **Jul. 12, 2004**

(57) **CLAIM**

We claim the ornamental design for a multi-panel computer display, as shown and described.

DESCRIPTION

FIG. 1 is a front perspective view of our design for a multi-panel computer display;

FIG. 2 is a rear perspective view thereof;

FIG. 3 is a front elevation view thereof;

FIG. 4 is a rear elevation view thereof;

FIG. 5 is a right side view thereof, the left and right sides are mirror images of each other;

FIG. 6 is a top view thereof; and,

FIG. 7 is a bottom view thereof.
